UNITED STATES PATENT OFFICE.

CARL AUGUST RUDQVIST, OF STAKET, SWEDEN.

IGNITION PLUG FOR INTERNAL-COMBUSTION MOTORS.

Application filed June 26, 1923, Serial No. 647,931, and in Sweden June 7, 1923.

This invention relates to improvements in ignition plugs for use in internal combustion engines and consists in certain means for rendering devices of this kind safe and 5 durable.

One object of the invention is to provide an electrically heated wire ignition plug, in which the difference in length due to the variation of the temperature to which the 10 different elements of the device are subjected, is entirely compensated.

Another object of the invention is to provide a device of this character, of such construction that the igniter element may be removed 15 from and replaced in the cylinder, and to this end is enclosed in a housing provided with a valve arrangement in order to ensure absolute tightness for the pressure gases in the cylinder, when the igniter element is removed from the combustion chamber.

A further object of the invention is to provide a safe and reliable insulation for the wire igniter element in order to prevent 20 short circuiting.

A further object of my invention is to provide an auxiliary igniting body with the object of keeping up the ignitions at times when the motor is running at reduced load 30 or when the load is thrown off, and with the further object of reducing the lapse of time during which the wire igniter element needs to be in operation on starting the motor.

A still further object of my invention is 35 to provide a construction wherein the igniting device may be indirectly cooled by means of a water jacket in the housing, said jacket at the same time reducing the temperature of the wall of the combustion chamber.

40 My invention is illustrated in the accompanying drawings as follows:

Figure 1 is a side elevation of one form 45 of ignition-plug embodying the features of the present invention, with the igniter element in its inoperative position.

Figure 2 is a vertical central section of 50 said plug with the igniter element in its operative position.

Figure 3 is a vertical central section, on 55 a smaller scale, of the combustion chamber of an internal combustion engine fitted with an ignition-plug constructed according to Figure 1.

Figure 4 is a vertical central section of a 60 modified form of the ignition-plug.

Figure 5 is a side elevation of said modified form of the ignition-plug.

Figure 6 is a vertical central section, on a smaller scale, of the combustion chamber of an internal combustion motor fitted with 65 an ignition-plug according to Figure 4.

The body or block 1, surrounding the hollow valve sleeve 2, is provided with threaded projections 3 and 4. Said projections are provided with bore holes communicating 70 with a hollow chamber or jacket 5 between the block 1 and the sleeve 2. Through jacket 5 a cooling medium, water or the like, may be led, the bore holes of the projections 3 and 4 serving as inlet and outlet respectively. At the lower end of sleeve 2 there is a threaded part 6 for attaching the ignition-plug to the motor, and also a conical part 7 serving as tightening means at the lower part of jacket 5. The upper part of 75 said jacket is made water tight by means of a packing 8 between tightening surfaces on the block and the sleeve. For tightening the ignition-plug against the motor the block 1 is provided with an off-set part 9. 80

At the upper end of sleeve 2 there is a hexagonal part 10 and two slits 11, 11', each extending axially from the top edge through the wall of the sleeve and terminating in a peripheral recess, as shown in Figure 1. 85 The slits are arranged diametrically or nearly diametrically opposite each other. The upper edge of sleeve 2 has two wedge-shaped surfaces 12, 13, also diametrically opposite each other, or approximately so, said 90 surfaces terminating in upwardly extending stops or projections 14, 15 respectively. In the slits 11, 11', locking springs 16, 16' are adapted to operate, said locking springs being rigidly connected to an axially movable 95 valve bushing 17, disposed in the hollow of sleeve 2.

In the position of bushing 17 shown in Fig. 1 the bent elastic parts 18, 18' of springs 16, 16' are resting against the cam surfaces 100 at 12, 13 at the upper end of sleeve 2. If the bushing 17 is rotated through a certain angle the elastic parts 18, 18' will be set so as to force bushing 17 upward. Secured in the lower end of bushing 17 by means of threads 105 20 is a housing 19 which encloses the igniter element 23. The housing is provided with an outwardly facing valve face 21. When the bushing 17 is forced upward by means of the springs 18, 18' mentioned above, said 110

valve face 21 will contact with a valve seat at the lower edge of sleeve 2, thus forming a tight joint and protecting the igniter element when the motor is running.

5 Owing to the elastic connection between parts 2, 16 and 17 the tightening action of valve face 21 will not become influenced by the changes of length of parts 2 and 17, due to the changes of temperature. The pitch of the wedge-shaped surfaces 12, 13 will set the springs 18, 18' a trifle more than is necessary to compensate for the length variations.

Between the valve face 21 and an upper valve face corresponding to a valve seat 22 of stud 2, the valve bushing 17 is guided in the body of the ignition plug by means of its cylindrical, closely fitting engagement with the sleeve 2.

In the position shown in Fig. 1 the igniter element is in inoperative position. In the position shown in Fig. 2, the element having been shifted to operative position, a conical shoulder or valve face on bushing 17 is forced into contact with the conical valve seat 22 of the valve sleeve 2. In this position, the locking springs 16, 16' are turned into the lower recesses of slits 11, 11', thus locking the bushing in its lowermost position in the sleeve 2. The upper parts of the locking springs being stiff, this locking action will become rigid.

The housing 19 is provided with side openings to admit the fuel to the igniter element enclosed therein. The igniter element consists of a spirally wound wire 23 and a rod 24, the lower end 25 of the rod being electrically connected to the wire. By means of a contact pin 27, the rod may be connected to a conduit wire 26, said conduit wire being attached to a contact piece 28, provided with a button 29, made of nonconducting material. The pin 27 is continued by a rod 30, threaded into an insulating nipple 31. At the lower end, the rod 30 by means of screw threads is connected to the upper end of rod 24. A guide bushing 32 for guiding rod 24 is rigidly fixed in bushing 17 between a tubular member 31' and the housing 19, said tubular member being screwed into the upper part of the valve bushing 17. A nipple 32' threaded into the guide bushing 32 surrounds an insulating bushing 34 for the upper part of rod 24. The upper part 35 of valve bushing 17 is provided with handles 36, diametrically oppositely disposed as shown by dot and dash lines in Figure 1.

The rod 24 is surrounded by a tubular insulating element 24' of quartz, glimmer or any other non-conducting material, arranged between the spirals of the wire and the rod. The object of this insulating element is to prevent the rod from coming into electrical contact with the spiral windings of the wire element 23, such a connection being liable to cause short-circuiting between the

rod and the spirals. Thus the electric current will pass through the whole spiral, causing the entire length to glow. Through the upper part 35 of the bushing 17 extend screws 37 connected to the inner parts of the locking springs 16 so as to rigidly fix said locking springs to the bushing 17. The upper part of the spiral igniter wire element 23 is fixed in the guide bushing 32, whereby electric connection with the body of the motor is established.

The locking elements may be provided with an extending bolt with spring elements at the upper and lower side to form elastic bearing surfaces on both sides of the locking elements.

When the engine is running at reduced load or when the load is thrown off, the temperature of the walls of the combustion chamber may not be sufficient to keep up the ignition. For this reason I have provided an auxiliary igniting device, arranged at the lower end of the igniting plug, which device will remain heated to such a degree that the ignition of the fuel will take place at the right moment. This device consists of a ball-shaped body or bulb 38, connected with housing 19 by means of a neck 39, as shown in Fig. 2. While the body and neck are shown herein as integral with the housing 19, it is obvious that they may be made separate therefrom and electrically connected thereto. Owing to the comparatively small dimensions of this body or bulb, the heat of the decreased combustion will be sufficient to keep up the temperature of the body to the required degree.

In the form shown in Figures 4 and 5 the igniting spiral *a* and the rod *b* are rigidly attached to the body or block *c*, said body being provided with a threaded part *d* for attaching the ignition plug to the combustion chamber *e*. In this modified form the igniter element is not movably arranged.

In order to protect the spiral wire element *a* from the heat of the combustion, when the motor is running, the body *c* is fitted with a cooling wall *f* surrounded by a water jacket *g* with pipe connections *h*' and *h*'' for the cooling water. This cooling arrangement may be regulated in such a manner that the wire element *a* will not become injured by the increased heat arising from the successive combustion in the cylinder. By means of the cooling action, it will be possible to maintain a lower degree of heat in the space between the wire *a* and the wall *f*, and the dimensions of said space may be chosen to suit the requirements.

Between the rod *b* and the spiral *a* an insulating bushing is inserted in order to prevent short-circuiting. At the upper end the rod *b* is formed into a contact pin *b*' for the contact socket *k* in the contact knob *j*, said contact socket being connected to an

electric conduit wire h' . The rod b is provided with a flange b^3 , which may be forced up against the upper surface of a bushing l closing up against a tightening face l' . To the lower end of said bushing, the wire element a is attached. The flange b^3 is forced up against the bushing l by means of a nipple m , screwed into a threaded socket n at the top of the body c . By unscrewing the nipple m , the igniter element a , b and bushing l may be taken out from the body c independently of the cooling jacket g . Between the flange b^3 and the adjoining faces of the nipple m and the bushing l washers of insulating material are inserted. The cooling wall f forms the cylindrical part of a bushing, at the upper end fitted with threads f^2 and screwed into the threaded socket n to form a water tight joint at the face f^3 . At the lower end the bushing is provided with a valve face f' , closing up against a corresponding seat at the lower end of the body c , the cooling water jacket being arranged between the valve arrangement f' and the joint f^3 . The conduits h' and h^2 , serving as inlet and outlet for the cooling water, are arranged in nipples h^3 and h^4 , attached to the body c by means of screws q . These screws are made hollow from one end, as shown in Figure 4, and the hollow spaces of the screws are connected to the conduits h' and h^2 respectively, as well as to the jacket space g . A tight connection between the conduit pieces is achieved by means of joints r .

The ignition plug described above may be used for all kinds of internal combustion motors of the semi-Diesel type or for other types requiring a specially heated igniter for starting or running.

It is obvious that changes in the form of construction and arrangements of parts of this device may be resorted to within the scope of the invention.

Having thus fully disclosed my invention, what I claim as new and desire to secure by Letters Patent is,

1. An ignition plug, comprising, in combination, a sleeve adapted to be secured in the cylinder wall of an internal combustion engine, a bushing axially movable in said sleeve and carrying an igniter element adapted to be retracted into and protracted from said sleeve, and a pair of resilient members carried by the bushing and adapted to engage said sleeve thereby to yieldably lock said bushing in its retracted position. 50

2. An ignition plug, comprising, in combination, a sleeve adapted to be secured in the cylinder wall of an internal combustion engine, said sleeve having a pair of diametrically opposite bayonet slots and provided at its upper edge with a pair of diametrically opposite cam portions, a bushing axially movable in said sleeve and carrying an igniter element adapted to be retracted into and protracted from said sleeve, and a pair of members carried by the bushing and each provided with a rigid portion and a resilient portion adapted to engage said 60 bayonet slots and said cam portions respectively for locking the bushing in its protracted and retracted positions. 70

3. An ignition plug, comprising, in combination, a sleeve adapted to be secured in the cylinder wall of an internal combustion engine, a bushing axially movable in said sleeve and carrying an igniter element adapted to be retracted into and protracted from said sleeve, said bushing and sleeve 75 having cooperating contact faces adapted to limit the protracting and retracting movement of the bushing, locking means for rigidly retaining the bushing in its protracted position and yieldably retaining it 80 in its retracted position, and an auxiliary igniter body carried by said bushing and adapted to be exposed in the cylinder when the first igniter element is retracted into the sleeve. 90

In testimony whereof I have signed my name to this specification.

CARL AUGUST RUDQVIST.
